Amherst, Feb. 8, 1870.

United States Patent Office.

NICHOLAS S. VEDDER, OF TROY, NEW YORK.

Design No. 3,859, dated February 22, 1870.

DESIGN FOR A STOVE-PLATE.

The Schedule referred to in these Letters Patent and making part of the same.

To all whom it may concern:

Be it known that I, NICHOLAS S. VEDDER, of the city of Troy, in the county of Rensselaer, and State of New York, have invented or produced a new and original ornamental Design for Plates of a Cooking-Stove, of which the following is a specification, reference being had to the accompanying photographic illustration.

The design for the large oven door F consists of the central compound ornament *g* and ornamental border *h*, shaped and disposed so as to appear as represented in the aforesaid photograph.

The design for the front fire-door I consists of the central ornament *j* and ornamental border *k*, shaped and arranged as shown in the above-mentioned illustration.

The design for the door or panel L, at the end of the fire-box, consists of the ornamental border *m* and central ornament *n*; that for the panel O in front of the oven-door, of the central ornament *p* and border *q*; and that for the upper front door R, of the border *s* and inside ornament *t*, the same being shaped and arranged so as to have the appearance represented in the photograph aforesaid.

What I claim as my invention or production, and desire to secure by Letters Patent, is—

The design for the plates or parts F, I, L, O, and R of a cooking-stove, as herein described and shown.

NICHOLAS S. VEDDER.
